UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,909, dated June 4, 1872.

To all whom it may concern:

Specification describing a new and original Design for a Carpet, invented by EDWARD POOLE, of Halifax, in the county of York, England.

The accompanying photograph fully illustrates my invention.

This invention relates to a new carpet design, in which, as main ornaments, two flower bouquets are drawn—one in a cross-shaped

figure with curved sides, and the other in a curvilinear octagon. The scrolls which fill the space between these figures constitute also an important feature of the design.

I claim as my invention—

The design for a carpet, as shown.

EDWARD POOLE.
